by *Derby, Oregon* Atty.

UNITED STATES PATENT OFFICE.

WILLIAM DONNER, OF DUBUQUE, IOWA, ASSIGNOR TO DRAPER COMPANY, OF HOPEDALE, MASSACHUSETTS, A CORPORATION OF MAINE.

LUG-STRAP HOLDER FOR LOOMS.

SPECIFICATION forming part of Letters Patent No. 760,972, dated May 24, 1904.

Application filed February 18, 1904, Serial No. 194,180. (No model.)

To all whom it may concern:

Be it known that I, WILLIAM DONNER, a citizen of the United States, residing at Dubuque, in the county of Dubuque and State of Iowa, have invented an Improvement in Lug-Strap Holders for Looms, of which the following description, in connection with the accompanying drawings, is a specification, like characters on the drawings representing like parts:

10 This invention has for its object the production of a strong, efficient, and cheap device to hold the lug-strap in proper position on the picker-stick in a loom, the holder being so constructed and arranged that it can be adjusted 15 along the picker-stick without the use of bolts or screws entering the same.

Probably the simplest and most common form of holder is a loop of leather secured to the outer edge of the picker-stick by a bolt or 20 screw, the lug-strap passing around the stick and through the loop.

When any change is necessary in the position of the holder, the fastening must be taken out and inserted higher up or lower down in 25 the picker-stick, as the case may be, the holes so made weakening the stick and being a prolific cause of breakage.

In my present invention the holder comprises a body portion which embraces the 30 picker-stick and is clamped thereon at the desired height, obviating the formation of holes in the stick and in no wise decreasing its strength.

The various novel features of my invention 35 will be described in the subjoined specification and particularly pointed out in the following claims.

Figure 1 is a front elevation of a portion of the picker-stick of a loom, the lug-strap, and 40 a lug-strap holder embodying one form of my invention. Fig. 2 is an enlarged outer end view of the device shown in Fig. 1. Fig. 3 is an inner end view thereof. Fig. 4 is a sectional detail on the line 4-4, Fig. 2, the picker-stick being shown in elevation. Fig. 5 is a 45 side elevation of a modified form of the lug-strap holder. Fig. 6 is a view of the body portion thereof opened out flat. Fig. 7 is an outer end view of the modification shown in Fig. 5,

and Fig. 8 is a perspective detail of the clamp- 50 ing member to be described.

Referring to Fig. 1, the picker-stick P, shoe S, on which it rocks, the picking-arm A, and lug-strap M may be and are all of usual or well-known construction.

In accordance with my invention the body of the holder is made of metal, preferably malleable iron, about one-sixteenth of an inch in thickness bent into the form of an elongated U, the bend 1 being increased in width, 60 the narrower extensions 2 being of sufficient length to project beyond the picker-stick when the holder is in position thereon. The bend 1 has on its inner face a thickened portion or boss 3, Fig. 4, provided with a threaded hole to receive a screw-bolt 4, the inner end of the latter pressing against a pronged holding device or catch, shown as a metal plate 5, having its end bent over at 6 and notched or pronged to enter the adjacent edge 70 of the picker-stick. A headed stud 7 is passed through the ends of the extensions 2 of the body, and a locking-nut 8 is screwed onto the threaded end of the stud, as shown clearly in Figs. 2 and 3. Between the extensions a 75 clamping-cam 9 is rotatably mounted on the stud, said cam being hollowed out, as shown in Fig. 4, to decrease its weight. The lower part of the cam has a lateral extension 10, upturned at its outer end at 11 to clear the body 80 of the holder and providing a finger-piece by which the cam can be set in clamping position.

As clearly shown in Fig. 4, the plate 5 engages the inner edge of the picker-stick, the latter passing between the sides of the U-shaped body, with the cam opposite the outer edge of the stick, and in said figure I have shown a second pronged or toothed plate 12, having teeth 13 to enter the wood of the stick, the cam acting upon the back of the plate 12. 90 When the cam is turned in the direction of arrow 14, Fig. 4, it presses the plate 12 against the outer edge of the picker-stick and acting through the sides of the body of the holder causes the screw-bolt 4 to press the pronged plate 5 against the inner edge of the stick, securely clamping the holder in place. The pronged plates by their engagement with the

picker-stick prevent the holder from becoming displaced accidentally. When the cam is set, the nut 8 is tightened, compressing the free ends of the body extensions 2 tightly 5 against the ends of the cam, so that the latter cannot work loose. One of the extensions 2 has a depending portion bent to form an upright loop 15, through which one side of the lug-strap M is passed, the strap being thereby 10 held in desired position with relation to the picker-stick. The top of the loop 15 is shown in Fig. 3 as bent in and downward at 16 to prevent lifting of the lug-strap, while the spring of the loop permits ready positioning 15 of the strap therein.

By means of the screw-bolt 4 the holder is adjusted to varying widths of picker-stick.

The construction is simple and cheap to manufacture, as the body of the holder can be 20 stamped out readily and the clamping-cam and finger-piece or handle 10 11 can be made as a casting.

If desired, a wrench can be applied to the finger-piece in setting up the cam.

25 The prongs of the plates 5 and 12 do not penetrate the wood of the stick far enough to injure or weaken it in any way.

In Figs. 5 to 8 I have shown a modified form of holder, and, referring first to Fig. 6, 30 the body consists of a substantially rectangular portion 17, toothed at its upper and lower edges, as at 18. Extensions 19 extend from each side of the portion 17, decreasing in width outwardly and terminating in depending 35 portions 20. Holes 21 are punched in the extremities of the extensions, and it will be seen that they and the depending portions 20 are symmetrical at each side of the central portion 17.

40 When the body is stamped out U-shaped, ears 22 are cut out in the extensions for a purpose to be described.

The body is bent along the dotted lines 17^x to bring the extensions 19 into parallelism, 45 and the toothed edges 18 are bent over and inward, as in Fig. 5, forming prongs which enter the edge of the picker-stick.

The ears 22 are bent down at the outer faces 50 of the extensions on the dotted lines 23, Fig. 6, into the position shown in Fig. 5, and the lower ends of the depending portions 20 are bent outward and upward, as at 24, along the lines 24^x, Fig. 6.

A clamping-cam 25 is eccentrically mounted 55 between the extensions 19 on a bolt 26, passed through the holes 21 and provided with a set-nut 27.

60 Referring to Fig. 8, the cam has at one end a polygonal extension 28, by which the cam can be set up, using a thin flat wrench or spanner, and then said cam is locked by tightening the set-nut 27. In this construction I obviate the use of separate pronged holding-catches, the prongs or teeth 18 engaging one 65 end of the picker-stick, while its other edge is

directly engaged by the cam 25, as is clearly shown in Fig. 5.

The lug-strap M (shown in dotted lines, Fig. 5) is vertically supported in the upturned loops 24 at each side of the picker-stick and 70 prevented from lifting by the overhanging ears 22.

75 My invention is not restricted to the precise construction herein shown and described, as the same may be modified or changed in various particulars without departing from the spirit and scope of my invention.

Having described my invention, what I claim, and desire to secure by Letters Patent, 80 is—

1. A lug-strap holder comprising a body adapted to embrace a picker-stick and having supporting means for the lug-strap, a pronged catch to engage the picker-stick, a clamping member to effect the operation of the said 85 catch and clamp the body in place upon the picker-stick, and locking means to hold the clamping member in operative position.

2. A lug-strap holder comprising a body adapted to be slidably mounted upon a picker- 90 stick and having supporting means for the lug-strap, holding-prongs to engage the picker-stick, means to operate the prongs and retain them in engagement with the picker-stick, and a locking device for said means. 95

3. A lug-strap holder comprising a substantially U-shaped body to embrace the picker-stick, a holding-prong located at the bend of the body and adapted to enter the picker-stick, a clamping-cam mounted on and between the ends of the body and adapted to force the holding-prong into the picker-stick, and means on the body independent of the 100 cam to support the lug-strap.

4. A lug-strap holder comprising a substantially U-shaped body to embrace the picker-stick, a pronged catch at one end of the body, a clamping-cam at the other end, a transverse stud on which the cam is rotatable, rotation of the cam forcing the catch into the material of the picker-stick, and means on the body independent of the cam to support and guide the lug-strap. 105

5. A lug-strap holder comprising a metallic body having integral means to support the lug-strap, a pronged catch and a clamping-cam, to act upon opposite faces of a picker-stick embraced by the body, and means to lock the cam in clamping position. 115

6. A lug-strap holder comprising a U-shaped metallic body having integral means to support and guide the lug-strap, a pronged catch within the bend of the body to engage the adjacent face of a picker-stick, a clamping-cam rotatably mounted between the two ends of 125 body, to operate the catch and clamp the body in position, and means to lock the cam from rotation when set.

7. A lug-strap holder comprising a U-shaped metallic body having integral means to support 130

and guide the lug-strap, a pronged catch within the bend of the body to engage the adjacent face of a picker-stick, a clamping-cam rotatably mounted between the two ends of the body, to operate the catch and clamp the body in position, and means to compress the ends of the body upon the clamping-cam and thereby lock it from rotation.

In testimony whereof I have signed my name to this specification in the presence of two subscribing witnesses.

WILLIAM DONNER.
